UNITED STATES PATENT OFFICE.

MARK A. PENNEY, OF DES MOINES, IOWA, ASSIGNOR TO WILLIAM L. CARPENTER, OF SAME PLACE.

WIRE-TWISTING MACHINE.

SPECIFICATION forming part of Letters Patent No. 291,765, dated January 2, 1884.

Application filed April 16, 1883. (No model)

To all whom it may concern:

Be it known that I, MARK A. PENNEY, a citizen of the United States, residing in Des Moines, in the county of Polk and State of Iowa, have invented a new and useful Improvement in Wire-Twisting Machines, of which the following is a specification.

This improvement relates to the twisters used more especially in connection with barb-fence machines; and it consists in the novel features hereinafter set forth.

In the accompanying drawings, Figure 1 is a side elevation of my invention, with the twisting-frame turned to a vertical position. Fig. 2 is a plan view of the same. Fig. 3 is a partial longitudinal section upon the line $x-x$ of Fig. 1. Fig. 4 is a partial cross-section upon the line $y-y$ of Fig. 1, and Fig. 5 is also a partial cross-section upon the line $z-z$ of Fig. 1.

Similar letters of reference indicate like parts wherever used in the drawings.

In the operation of my machine the wire passes first through the hollow journal thereof at A, thence over a sprocket-wheel, A', located near the mouth of the journal, and thence to a traversing and distributing sprocket wheel, B. This sprocket-wheel has a laterally-extended hub upon one side, whereon a worm, b, is cut, and it revolves upon a sleeve, c, loosely encircling the shaft D, which is supported at either end in the twisting-frame A'. The sleeve c is made integral with or attached to the arm C, and the wheel B is confined thereon by the collar and set-screw c' c''. In the arm C is journaled a shaft, E, lying longitudinally in the frame, upon one end of which shaft is a worm-wheel, e², meshing with the worm b, and upon the other end whereof is a pinion, e, which gears with rack E', secured upon the cross-bar E' of the frame. A collar, e', upon the extreme end of the shaft E, as said shaft rotates, bears against the inner surface of an elliptical guide, E'', surrounding the rack E'.

The operation of the distributor-wheel in this construction is as follows: The wires, as they pass to the spool, operate the wheel B in precise accordance with the speed at which they pass over the same. The operation of this wheel operates also the worm, and the

worm operates its wheel and the pinion e. 50 The pinion e, by reason of its engagement with the rack, traverses said rack, and carries with it in that movement the distributor-wheel and all the intervening parts. When the pinion reaches the end of the rack, it revolves around 55 the end thereof, being caused to do so by the guide E'', and thence travels back in the opposite direction, its teeth meshing with the opposite side of the rack, thus giving said pinion an endless path, in which it moves always 60 in the same direction, and enabling me to dispense with the reversing devices usually employed in twisters and fliers. The change in the angle of the pinion-shaft due to the endless path motion at the pinion end is accommodated by the attachment of the arm C to the shaft D, such attachment permitting both oscillation and sliding.

The spool is placed upon the shaft F, and secured to the head F', one face of which is 70 toothed to mesh with a pinion, f, (in broken lines) upon a shaft, f', actuated by pulley f'', receiving power by chain, belt, or otherwise from the pulley f''' upon the journal G at this end of the frame. The tension-exerting devices are applied to the pulley G' in any of the usual ways, said pulley being loose upon the journal, and said pulley f''' being fast to said tension-pulley, and likewise loose upon said journal. 80

H H' are the gears, whereby the frame is operated.

My invention permits the use of a plain shaft to support the distributing-wheel, instead of the right and left threaded one usually employed.

I claim—

1. The combination, with a distributing-wheel adapted to be actuated by the wire passing over it, and a plain shaft for supporting 90 the same, of devices actuated from the distributing-wheel, for imparting a to-and-fro movement to said wheel, substantially as specified.

2. The combination, with the rotating distributing-wheel and a plain shaft for supporting the same, and upon which it slides to and fro, of the frame, the rack stationary 95

therein, and a pinion traversing said rack, and connected to said wheel, so as to be actuated thereby, substantially as specified.

3. The combination, with the frame and distributor-wheel of a twister, of a device for imparting a traversing movement to said wheel, consisting of the rack, the pinion traveling around said rack in an endless path, and the intermediate devices connecting the wheel and pinion, substantially as specified.

4. The distributor-wheel, in combination with the rack, the surrounding guide, the pinion and collar traveling around said rack and guide, and the intermediate devices, whereby

the motion of the wheel is communicated to 15 said pinion and collar, substantially as specified.

5. The combination of the distributor-wheel, the worm on the hub thereof, the arm provided with the sleeve on which the wheel rotates, and said sleeve, with the shaft D, the worm-wheel, the pinion, the rack, the surrounding guide, and the collar, acting in conjunction with the guide, substantially as specified.

MARK A. PENNEY.
